UNITED STATES PATENT OFFICE.

WINFIELD A. ATWOOD, OF SCHENECTADY, NEW YORK, ASSIGNOR TO GENERAL ELECTRIC COMPANY, A CORPORATION OF NEW YORK.

INSTRUMENT SHUNT.

Application filed April 9, 1925. Serial No. 22,001.

My invention relates to instrument shunts of the type adapted to be inserted in an electric circuit so as to shunt a definite portion of the current flowing therethrough to an instrument or other device which is to be responsive to the line current.

As usually constructed, instrument shunts are made of copper, or of a material containing a large percentage of copper, in order to make the temperature coefficient of resistance zero, or very low. The temperature coefficient of resistance of such a shunt is fixed and is not subject to adjustment for different instruments. High capacity copper shunts having the requisite resistance drop thereacross and the heat dissipating capacity necessary for continuous heavy service are relatively expensive.

The object of my invention is to provide a rugged, relatively inexpensive shunt arranged so that its temperature coefficient of resistance may be readily adjusted to accommodate different instruments or other devices.

In carrying my invention into effect I provide a shunt made up of relatively inexpensive materials having different temperature coefficients of resistance, the two materials being so arranged that the line current flows in parallel therethrough and, so that the relative resistance effects of the different materials may be adjusted with respect to each other and in this way obtain a desired resultant temperature coefficient of resistance.

In the construction of my shunt, I prefer to use cast iron and carbon since these materials are relatively inexpensive and have opposite temperature coefficients of resistance. The preferred construction takes the form of a corrugated cast iron casing enclosing an adjustable stack of carbon discs so arranged that the current flowing through the shunt flows in parallel through these materials. By adjusting the relative resistances of these two paths the temperature coefficient of resistance of the shunt may be changed. The features of my invention which are believed to be novel and patentable will be pointed out in the claims appended hereto. For a better understanding of my invention, reference is made in the following description to the accompanying drawing in which Fig. 1 represents a side view, partially in

section of my improved shunt; and Fig. 2 represents an end view thereof.

Referring to the drawing, the main body of the shunt constitutes a cylindrical member 10, preferably deeply corrugated to facilitate the dissipation of heat therefrom and preferably made of cast iron. The end surfaces of this member are machined and constitute the line connections. Threaded bolt holes 11 are provided for the connection of the line terminals which are bolted in position in the manner indicated at 12. The central bore of the cylindrical member is threaded as represented at 13 and contains one or more disks 14, preferably of carbon, or other material having similar properties, compressed between adjustable nuts 15. The adjusting nuts are preferably made secure by lock nuts 16. Two or more shunt lead terminal bolt holes, represented at 17, 18, 19, 20 and 21, are provided to attach the leads which connect with the measuring instrument or other device used with the shunt. It will be evident that this shunt is relatively inexpensive, both as to the cost of the materials used and the mechanical operations necessary for its construction.

Cast iron has a positive temperature coefficient of resistance and, consequently, would not be suitable as a shunt if used alone. Carbon, on the other hand, has a negative temperature coefficient of resistance and likewise is not suitable for this purpose. However, by the proper combination of these materials in parallel, a desirable compromise temperature coefficient may be obtained which, as will be more fully explained hereinafter, may readily be altered to suit different instruments. Cast iron and carbon both have positive temperature coefficients of expansion, that of a suitable grade of carbon being somewhat higher than that of cast iron. It will therefore be evident that as the shunt heats up, the cast iron will expand at a slightly less rate than the carbon discs 14, and this action will compress the carbon discs and decrease the resistance therethrough. This has the same effect on the characteristics of the shunt as the negative temperature coefficient of resistance of the carbon has. The line current in flowing through the shunt will pass entirely through the cast iron portion except that portion lying between the two sets of nuts 15 and 16.

Between these points part of the current will flow through the carbon discs. It will therefore be evident that to obtain a shunt having a zero temperature coefficient of resistance across the extreme shunt terminals 17 and 18, the resultant temperature coefficient of resistance of that portion of the shunt having the iron and carbon connected in parallel must be negative to make up for positive temperature coefficient of resistance of the remaining portion of the shunt which is entirely of iron. There are a variety of ways in which to change the resultant temperature coefficient of the shunt between the shunt terminals. For example, the number, thickness or diameter of the carbon discs may be changed and one of the discs has been represented as being thinner and of a less diameter than the others for this purpose. A slight adjustment may also be had by tightening or loosening the clamping nuts which compress the carbon discs. It will also be evident that for any given adjustment the temperature coefficient of resistance across terminals 17 and 18 will be different than that across terminals 18 and 19, since that portion of the shunt between terminals 17 and 19 is entirely positive. Any of these changes will also change the voltage drop across any set of terminals for a given line current and temperature. The manner of adjusting the shunt for a given temperature coefficient of resistance and voltage drop will be clearer by taking a specific case. Suppose it is desired to provide a shunt having a zero temperature coefficient of resistance and a 1 volt drop for 1000 amperes line current. The shunt will be constructed with the general proportions calculated to give this result. Suppose that when assembled as illustrated in Fig. 1, the shunt gives 2.1 volts across terminals 17 and 18 and has a temperature coefficient which is slightly negative. It will appear that to correct the temperature coefficient, we must reduce the effect of the carbon path and this will increase the total drop across the shunt. Consequently, it will be necessary to use shunt terminals 18 and 21 or possibly 18 and 20. The effect of the carbon path may be reduced by reducing its length or increasing its resistance. A slight loosening of one set of nuts may be sufficient. If not, a disc may be removed entirely or replaced by one of less thickness or less diameter and the nuts again screwed down to the proper tension. The two conditions to be met must be considered together but by providing a sufficient number of shunt terminals of slightly different spacing as represented at 19, 20, 21 and 17 and a suitable variety of extra carbon discs these conditions may be met. The various carbon discs will preferably be marked or otherwise identified and the shunt terminals marked so that after the shunt is

once calibrated, a calibration record may be prepared and used to facilitate obtaining the same or other desired adjustments.

It will be seen that different terminals of this shunt may be used to simultaneously obtain voltage drops proportional to the line current having slightly different resistance temperature coefficient characteristics. Thus, the same shunt may be simultaneously used to operate an instrument having a zero temperature coefficient of resistance and a relay having a positive temperature coefficient of resistance.

I do not wish to limit my invention to cast iron and carbon as the materials to be used, nor do I wish to limit my invention to materials which have different temperature coefficients of expansion, since it will be evident that there are various grades of iron and steel as well as various grades of carbon and substitutes for carbon which may be combined in accordance with the teachings of this invention to obtain the beneficial result thereof. Other modifications will occur to those skilled in the art and, consequently, I do not wish to be limited to the particular embodiment of my invention herein described, but intend to cover in the appended claims all modifications and embodiments coming within the true spirit and scope of my invention.

What I claim as new and desire to secure by Letters Patent of the United States, is:—

1. An electric shunt comprising a conducting member having a positive temperature coefficient of resistance, a conducting member having a negative temperature coefficient of resistance connected in parallel with a portion of the first mentioned member, and shunt lead terminals adjacent the extremities of said shunt, said conducting members having their relative resistances adjusted so as to produce a substantially zero temperature coefficient of resistance characteristic across said shunt lead terminals. 100 105 110

2. An electric shunt comprising a conductor having a given temperature coefficient of resistance, means for securing line connections to the extremities of said conductor, shunt lead terminals adjacent the extremities of said conductor, a second conductor having a temperature coefficient of resistance opposite to that of the first mentioned conductor and connected in parallel with said first mentioned conductor between the extremities thereof, and means for adjusting the resistance of said second mentioned conductor. 115 120 125

3. An electric shunt comprising a conductor having a positive temperature coefficient of resistance, means for securing line connections to the extremities thereof, shunt lead terminals adjacent the extremities of said conductor and an adjustable carbon pile con- 130 135

nected in parallel with a portion of said conductor.

4. An electric shunt having parallel connected conductor circuits of positive and

5 negative temperature coefficients of resistance respectively, and means for adjusting the relative resistance effects of said parallel connected circuit.

5. An electric shunt comprising a conductor having a positive temperature coefficient of resistance, line terminals therefor, shunt lead terminals adjacent said line terminals, a conductor having a negative temperature coefficient of resistance connected in parallel 15 with a portion of said first mentioned conductor, and means for adjusting the length of the parallel connected portions of said conductors.

6. An electric shunt comprising a cast-iron member having an opening through one axis thereof, line terminals and shunt lead terminals adjacent the extremities of such axis, a carbon pile in said opening electrically connected in parallel with the adjacent 25 portion of said cast-iron member, and means for adjusting the length and the compression of said carbon pile.

7. An electric shunt comprising a corrugated cast-iron member having a cylindrical 30 opening through one axis thereof, line termi-

nals and shunt lead terminals adjacent the extremities of such axis, nuts threaded in said opening and a carbon pile compressed between said nuts.

8. An electric shunt having line terminals, different portions of said shunt between said line terminals having different temperature coefficients of resistance and means for connecting shunt leads across different portions of said shunt so as to obtain a desired 35 resultant temperature coefficient of resistance characteristic.

9. An electric shunt having line terminals, different portions of said shunt between said line terminals having different temperature coefficients of resistance, means for varying the temperature coefficients of resistance of one portion of said shunt, and means for connecting shunt leads across different 40 portions of said shunt whereby a desired 50 voltage drop and temperature coefficients of resistance characteristic may be obtained.

10. An electric shunt comprising parallel conductors having different temperature coefficients of expansion and opposite temperature coefficients of resistance secured in fixed 55 relation with each other.

In witness whereof, I have hereunto set my hand this 8th day of April, 1925.

WINFIELD A. ATWOOD.
